CLAIM

The ornamental design for a display screen with graphical user interface, as shown and described.

DESCRIPTION

The patent or the application file contains at least one drawing executed in color. Copies of this patent or patent application publication with color drawing(s) will be provided by the Office upon request and payment of the necessary fee.

The sole FIGURE is a front view of a display screen with graphical user interface showing my new design.

The broken rectangle showing the display screen is included for the purpose of illustrating portions of the article and forms no part of the claimed design.
